Patented Apr. 12, 1921.

INVENTOR

John Q. Keller

UNITED STATES PATENT OFFICE.

JOHN O. KELLER, OF CINCINNATI, OHIO, ASSIGNOR OF ONE-HALF TO FRED W. KELLER,
OF COVINGTON, KENTUCKY.

EGG-TESTER.

1,374,577.

Specification of Letters Patent. Patented Apr. 12, 1921.

Application filed July 17, 1919. Serial No. 311,568.

To all whom it may concern:

Be it known that I, JOHN O. KELLER, a citizen of the United States, residing in Cincinnati, in the county of Hamilton and 5 State of Ohio, have invented new and useful Improvements in Egg-Testers, of which the following is a specification.

An object of my invention is to produce a device for testing or candling eggs in a more 10 reliable and simple manner than has been done heretofore.

A further object is to produce a device for candling eggs in the presence of a customer, as is required by law in much more rapid 15 and easy manner than has been possible heretofore.

These and other objects are attained in the egg candling device described in the following specification and illustrated in the accompanying drawing which illustrates an egg candling device embodying my invention.

Although my improved device may be made of wood, I have chosen to illustrate the 25 embodiment as being made of metal.

In the device shown, a cabinet or box consisting of a back 1, sides 2 and 3, a bottom 4, a top 5, and a front 6, is provided. A portion of the front of the cabinet is open, 30 a door 7 being provided for closing the open portion. To keep door 7 closed I preferably provide spring hinges 8 and 9, a knob 10 being provided to open the door. Within the space closed by the door I provide slides 35 11, 12 and 13 upon which drawers may be slid, one drawer 14 being shown in position on slides 11 and partially within the cabinet. Each drawer consists of a front 15 to which an egg-supporting platform 16 is attached, 40 the sides 17 being bent down with inturned edges which rest upon the slides. The platform of each drawer is provided with perforations 18 having depressed edges 19 in which the blunt end of the eggs rest as shown. To permit the drawers to be removed easily I have provided each with a finger notch 20 in its front 15.

Above the top drawer I provide a means of illumination, such as an electric lamp 21 50 in the back of the cabinet. Above the lamp I provide a reflector 22 to cast the rays of illumination downwardly and in each end of the cabinet I provide ventilators 23 and 24, a ventilator in the top, not being shown.

To provide access to the lamp 21 I provide 55 the top 5 with hinges 25 and 26.

At the bottom of the cabinet I provide reflecting surfaces 27 in the back, 28 in the bottom, and 29 in the sides. These surfaces may be provided either by polishing the inner surfaces of the cabinet walls and bottom 60 until they sufficiently reflect the under sides of the eggs in the drawers, or by providing inserts of pieces of mirror.

In using my improved device it is but 65 necessary to fill a drawer with the eggs by placing the blunt ends thereof within the perforations 18. The drawer is then placed within the cabinet, the door 7 being allowed to close. The lamp 21 is then illuminated, 70 the rays therefrom passing through the eggs and being reflected in the reflecting surfaces 27, 28, and 29 as represented by images 30. Any bad eggs in those in the drawer will be 75 readily shown in reflections 30. As soon as 75 the eggs have been tested, another drawer may be slipped in position, the three drawers permitting the several clerks in a store to use the device substantially simultaneously, one clerk filling, another testing, and another 80 emptying the eggs for as many customers.

Having thus described my invention what I claim is:—

An egg tester comprising a cabinet having a drawer containing compartment, a series 85 of drawer slides in the drawer-containing compartment, adapted to receive one or more drawers, a series of bottomless skeleton drawers having notched fronts, adapted to occupy the slides, the fronts substantially closing the drawer containing compartment, a lamp containing compartment above the drawer containing compartment, a reflector above the lamp in the lamp containing compartment, doors closing the lamp-containing 90 and drawer-containing compartments, and a reflecting compartment beneath the drawer-containing compartment, said reflecting compartment having a reflecting surface on each of its inner walls and having an open front 95 rendering each reflecting surface visible at a distance from the tester.

In witness whereof, I affix my signature in the presence of two witnesses.

JOHN O. KELLER.

Witnesses:

CHAS. BUSCHMAN,
WILLIAM J. SCHULTZ.
